EXPANSION RAILS

Edwin Watson, 1101 Bowles Ave., Littleton, Colo.

Filed May 1, 1959, Ser. No. 810,272

1 Claim. (Cl. 238—179)

This invention relates to an expansion rail for railroad tracks. Difficulties are encountered in keeping railroad rails in perfect condition and alignment due to temperature expansion in the rails. This difficulty is becoming more aggravated since the welding of the rails into continuous exceedingly long lengths is present practice. In certain locations, differences in atmospheric temperature of possibly 100° to 120° F. is encountered. This range of temperature causes considerable expansion in each individual rail length and when they are welded together, the expansion is, of course, multiplied to the destruction of the track.

The principal object of this invention is to provide an expansion rail which can be inserted along the track at selected points and which will operate to efficiently and safely accommodate the temperature expansions and contractions in the rails without affecting the running qualities of the rails.

Another object of the invention is to provide an expansion rail for the above purpose which will have perfect expansion characteristics without interfering with the load carrying capacity of the track and without creating wheel noises.

Other objects and advantages reside in the detail construction of the invention, which is designed for simplicity, economy, and efficiency. These will become more apparent from the following description.

In the following detailed description of the invention, reference is had to the accompanying drawing which forms a part herof. Like numerals refer to like parts in all views of the drawing and throughout the description.

In the drawing:

Fig. 1 is a fragmentary perspective view of one side of the midportion of the improved expansion rail;

Fig. 2 is a similar perspective view of the other side thereof; and

Fig. 3 is an enlarged cross section through the expansion portion of the rail taken on the line 3—3, Fig. 1.

The improved expansion rail may be of any desired length, preferably of a length to correspond to a standard rail length. The complete expansion rail is formed in two longitudinally aligned rail sections 10 and 11. One extremity of the section 10 is cut back to form a narrow overlapping extremity 12, and the section 11 is similarly cut back to form a similar overlapping extremity 13, so that when the two overlapping extremities are faced together, as indicated by the joining line 16, the combined width of the two overlapping extremities will equal the standard rail width of the rail sections 10 and 11.

The overlapping extremity 12 of the rail section 10 is provided, on its inner face, with a longitudinally extending dove-tailed key 17. An indented guide groove 18 is formed along the upper edge of said inner face and a guide flange 19 extends longitudinally along the lower edge thereof.

The inner face of the overlapping extremity 13 of the rail section 11 contains a longitudinally-extending dove-tailed groove 22 which slidably receives the dove-tailed key 17. The latter inner face is provided with an upper edge flange 20 which slidably engages in the guide groove 18 of the extremity 12 and with a receiving groove 21 along its lower edge for slidably receiving the guide flange 19.

2

The two rail sections 10 and 11 are joined together in slidable engagement, as shown in Figs. 1 and 2 to form a complete expansion rail of substantially standard rail length, which can be inserted in the track in place of a standard rail. The distant extremities of the two rail sections 10 and 11 will be prepared in any of the conventional ways for connection with the adjacent rails. For instance, they may be prepared for welding to the adjacent rails or they may be drilled for the attachment of the conventional fish plates and bolts.

It can be seen that with these expansion rails inserted in the track, the latter can freely expand and contract in accordance with temperature changes, for the overlapped, slidably engaged extremities of the two rail sections 10 and 11 allow free longitudinal movement.

The plurality of horizontal ledges provided by the dove-tailed key 17 and its dove-tailed slot 22 and the surfaces of the guide flange 19 with its receiving groove 21 and the edge flange 20 with its aligning groove 18 maintain the two rail sections in rigid horizontal and vertical alignment. The web of the overlapping extremity 12 is thickened, as indicated at 14, and the overlapping extremity 13 is similarly thickened, as indicated at 15, so that the overlapped extremities will have the same rail strength as the remainder of the rail. The thickened portions balance the overlapped web on each side of the longitudinal center line, as indicated at "A" in Fig. 3.

A wheel rolling along the expansion rail will roll from one rail section onto one overlapping extremity thence onto the double overlapped extremities at each side of the joining line 16, thence onto the other overlapped extremity 13, and thence onto the other rail section 11 without noise or vibration.

While a specific form of the improvement has been described and illustrated herein, it is to be understood that the same may be varied within the scope of the appended claim, without departing from the spirit of the invention.

Having this described the invention what is claimed and desired secured by Letters Patent is:

An expanding railway rail comprising: a first rail section; a second rail section; said sections having a cross section corresponding to a conventional railway rail for the major portions of their lengths; a narrowed extremity formed on each section, said extremities being overlapped to form a longitudinally split overlapped portion corresponding in width to the remainder of said rail sections; a dove-tailed key extending longitudinally of the inner face of the first overlapping extremity; a dove-tailed groove formed in the inner face of the second overlapping extremity and slidably receiving said key; a projecting longitudinally-extending guide flange formed along the lower edge of the inner face of the first overlapping extremity and slidably engaging a receiving groove in the lower edge of the inner face of the second overlapping extremity; a guide groove formed along the upper edge of the inner face of the first overlapping extremity; and a longitudinally extending upper guide flange formed on the upper edge of the inner face of the second overlapping extremity and slidably engaging said guide groove, the two extremities being unattached against relative longitudinal movement.
